CONVERTIBLE SHOE
Lorren R. Pike, 5624 El Arado Way, Sacramento, Calif.
Filed Oct. 20, 1964, Ser. No. 405,028
4 Claims. (Cl. 36—2.5)

This invention relates to shoes and, more particularly, to a shoe which is convertible between a heelless type shoe and a shoe having an upper heel portion.

It is an object of the present invention to provide a comfortable and convenient shoe which can be readily converted for use with and without an upper heel portion, whereby such can be readily worn as a sandal or as a dress shoe for various occasions.

Another object of the present invention is to provide a convertible shoe of the type described having an upper heel portion which can be readily detached or used, without discomfort to the wearer, and without detracting from the appearance or usefulness of the shoe.

Still an additional object of the present invention is to provide a convertible shoe of the aforementioned type which is simple in construction, can be manufactured at relatively low cost, and which is highly attractive in appearance and desirability.

All of the foregoing and still further objects and advantages of this invention will become apparent from a study of the following specification, taken in connection with the accompanying drawing, wherein:

FIGURE 1 is a side elevational view of a convertible shoe made in accordance with one form of the present invention, in actual use;

FIGURE 2 is a fragmentary perspective view of certain parts of the shoe shown in FIGURE 1, with the upper heel portion removed;

FIGURE 3 is a perspective view of the upper heel portion forming a part of the shoe shown in FIGURE 1;

FIGURE 4 is a fragmentary longitudinal cross sectional view of a slightly modified form of construction; and

FIGURE 5 is a perspective view of the internal frame of the upper shoe portion shown in FIGURE 4, showing details thereof.

Referring now more in detail to the drawing, and more particularly to FIGURES 1 to 3 thereof, a convertible shoe 10 made in accordance with the present invention is shown to include a sole member 12 having a rear surface portion 14 for receiving the heel of a foot, and having a depending structural heel 16.

The rear surface portion 14 of the sole, defines a rearwardly opening socket 20 in the form of an aperture lying in a plane intermediate the upper surface portion and the structural heel 16, for slidably receiving a forwardly projecting tab 22 of a heel receiving upper 24 of any suitable construction and design. This tab 22 is integral with a frame portion 26 which, when the heel upper is applied to the shoe, snugly engages with the sides of the rear surface portion 14 of the sole to provide a finished appearance. A tie string 28, strap, or the like, is carried by the heel upper 24 for engagement with the foot of the wearer, thus serving to maintain the heel upper in assembly with the shoe and providing support for the wearer.

It will thus be recognized that upon removal of the heel upper 24, the shoe 10 can be comfortably worn as a sandal.

Referring now to FIGURES 4 and 5 of the drawing, a slightly modified form of construction 30 is shown wherein the sole 32 has an upper portion 34 that defines a for-

2

wardly and upwardly opening slot 36 which receives a depending and rearwardly extending tab 38 of the frame 40 of a removable heel upper 42. This frame 40 also includes an upwardly projecting stiffener member 44 and side frame 46 for adding body to the upper 42 to sustain the foot of the wearer without any additional reinforcement or strap. The heel upper 42 also includes a heel pad 48 that overlies the opening 36, and frame portion 40, to avoid discomfort to the wearer. When the heel upper is removed from the shoe, simply by forwardly disengaging it from the sole portions, the heel pad may be applied directly to the upper surface of the portion 34 to provide similar protection against discomfort to the wearer because of the aperture 36.

It will now be appreciated that an extremely simple, highly styled, and convenient shoe has been provided which can be readily converted by the user for various occasions.

While this invention has been described with particular reference to the construction shown in the drawing, it is to be understood that such is not to be construed as imparting limitations upon the invention, which is best defined by the claims appended hereto.

Having thus described my invention, I claim as new and desire to secure by Letters Patent:

1. A convertible shoe comprising, in combination, a sole having a rear surface portion for receiving the heel of a foot and having a depending structural heel, a shoe upper having lower marginal portions corresponding to the outline of an upper extremity of said structural heel, a mounting plate carried by said shoe upper above said lower marginal portions thereof, and said rear portions of said sole having a terminal section defining socket means detachably receiving said mounting plate of said upper with said lower marginal portions of said shoe upper enveloping said upper extremity of said structural heel to mask said mounting plate and socket means from view externally of said shoe.

2. A convertible shoe as set forth in claim 1, wherein said socket means comprises a rearwardly opening aperture in the terminal section of said sole, said aperture lying in a plane intermediate said surface portion and said structural heel and opening rearwardly outwardly, said mounting plate comprising a forwardly protruding tab carried by said upper slidably received within said aperture.

3. A convertible shoe as set forth in claim 1, wherein said socket means comprises a forwardly and upwardly opening aperture defined by said rear surface portion of said sole, and said mounting plate comprising a rearwardly projecting tab carried by said upper slidably receivable within said aperture.

4. A convertible shoe as set forth in claim 3, wherein said upper further comprises a heel pad overlying said aperture and said tab.
